(57) **CLAIM**

The ornamental design for a protective covering for saddle of bicycle, as shown and described.

DESCRIPTION

FIG. 1 is a front perspective view of a protective covering for saddle of bicycle showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a perspective view thereof, illustrating attachment of the protective covering onto a saddle of a bicycle.

The broken lines shown are for illustrative purposes only and form no part of the claimed design.
